UNITED STATES PATENT OFFICE.

FREDERICK T. FLINCHBAUGH, OF YORK, PENNSYLVANIA, ASSIGNOR TO WAYNE TOOL MANUFACTURING COMPANY, OF WAYNESBORO, PENNSYLVANIA, A CORPORATION OF PENNSYLVANIA.

PORTABLE REBORING MACHINE FOR ENGINE CYLINDERS.

Application filed September 30, 1921. Serial No. 504,286. Renewed June 14, 1924.

To all whom it may concern:

Be it known that I, FREDERICK T. FLINCHBAUGH, citizen of the United States, residing at York, in the county of York and State of Pennsylvania, have invented certain new and useful Improvements in Portable Reborning Machines for Engine Cylinders, of which the following is a specification.

This invention relates to an improved portable cylinder reborning machine particularly designed for the use in reborning the cylinders of internal combustion engines, and has as one of its principal objects to provide a sturdy, compact and easily operated machine of this character for reborning a cylinder with accuracy.

A further object of the invention is to provide a machine adapted for a wide range of use as regards difference in the diameter of the bore to be cut.

A still further object of the invention is to provide a machine embodying a variable feed and wherein the mechanism provided for controlling the feed will be conveniently accessible.

The invention has as a still further object to provide a machine wherein the cutter employed may be easily and quickly backed out of a cylinder without revolving the cutter or revolving the boring bar employed.

And the invention has as a still further object to provide a machine which, after being centered with respect to a cylinder, may be detached from the base employed for inspecting the work without molesting the centering of the base so that the machine may be replaced upon the base and the cutting operation continued without the necessity for again centering the machine.

Other and incidental objects will appear hereinafter.

In the drawings:

Figure 1 is a perspective view of my improved reborning machine.

Figure 2 is a transverse section on the line 2—2 of Figure 1, looking in the direction of the arrows.

Figure 3 is a fragmentary vertical sectional view,

Figure 4 is a section on the line 4—4 of Figure 3, looking in the direction of the arrows,

Figure 5 is a fragmentary sectional view

particularly illustrating the rack sleeve of the boring bar,

Figure 6 is a transverse sectional view on the line 6—6 of Figure 3,

Figure 7 is a transverse section on the line 7—7 of Figure 4, looking in the direction of the arrows, and

Figure 8 is a perspective view showing the crank employed.

In carrying the invention into effect, I employ a cylindrical base 10 which is provided in the sides thereof with sight openings 11 and formed on the base at its lower end is a plurality of lugs 12 with which may be engaged suitable clamps connecting the base with an engine block centered with respect to one of the cylinders of the engine. In Figure 1 of the drawings, I have conventionally shown an engine block at 14. At its upper end the base is provided with oppositely disposed ears 15 and removably fitting upon the base is a gear case 16. This gear case is provided with ears 17 mating with the ears 15 and coacting with said ears are cap bolts 18 detachably connecting the gear case with the base. Formed on the bottom wall of the gear case axially thereof is, as particularly shown in Figure 4, a depending bearing 19 and closing the gear case at its upper end is a cover plate 20 having an upstanding bearing tube 21 alining with the bearing. Securing the cover in position are cap bolts 22 threaded into the gear case.

Snugly but rotatably fitting in the bearing tube 21 to extend through the bearing 19 journaled thereby is a boring bar 23 provided at its upper end portion with a reduced stem 24 at the inner end of which is an annular shoulder 25 and journaled upon the stem is a rack sleeve 26 slidably fitting in said tube. Interposed between the lower end of the sleeve and the shoulder 25 is a thrust washer 27 which is preferably of fiber and formed on the upper end of the stem 24 is a stud 28 over which is fitted a washer 29 coacting with the upper end of the sleeve. Threaded upon said stud is a nut 30 coacting with the washer and securing said nut against accidental displacement is a jam nut 31. At one side, the sleeve is provided with a rack 32 extending from end to end of the sleeve and formed in the sleeve in spaced

relation to said rack is, as particularly shown in Figure 2, a longitudinally directed slot 33. Threaded through the wall of the tube 21 is a pin 34 having a smooth inner end 35 slidably engaging in said slot for holding the sleeve against rotation and threaded upon the outer end of said pin is a lock nut 35 securing the pin in position. At its inner end, the boring bar 23 carries a cutter head 36 upon which is mounted a plurality of radial cutters 37 but since the specific construction of the cutter head as well as the cutters does not concern the present invention, these parts will not be described in detail.

Formed in the boring bar 23 at one side thereof is a longitudinally extending slot 38 and surrounding the bar within the gear case 16 is a beveled gear 39 having a hub 40 coacting with the bottom wall of the casing. Threaded through this hub are spaced cap bolts 41 having smooth inner ends slidably engaging in the slot 38 so that a driving connection between the beveled gear 39 and boring bar is thus provided while, at the same time, the boring bar may shift longitudinally through the gear. Formed on the cover plate 20 of the gear case at one side of said plate is a gear housing 42 from which projects a lateral bearing 43 and extending through said bearing into the housing is a drive shaft 44 squared at its outer end. Fixed to the inner end of said shaft is a double beveled pinion having gear teeth 45 and 46 respectively, the gear teeth 45 meshing with the teeth of the beveled gear 39 so that when the drive shaft is turned the boring bar will be rotated for revolving the cutter head. Closing the gear housing 42 is a cover plate 47 secured by suitable cap bolts and formed on said plate is an upstanding bearing 48 provided at its upper end with an overhanging end plate 49 on which is formed a bearing 50. Journaled through the bearing 48 is a feed gear shaft 51 extending into the gear housing 42 and fixed to the lower end of said shaft within the housing is a beveled gear 52, the teeth of which mesh with the teeth 46 of the double beveled pinion upon the drive shaft 44.

Formed on the bearing tube 21 at its upper end is, as particularly shown in Figure 2, a transversely disposed barrel 53 at one end of which is a bearing 54 and formed on the tube at the opposite end of said barrel is a boss 55 lying flush with the adjacent end of the barrel. Mounted upon said boss is a circular guard plate 56 having a peripheral flange 57 and formed on said plate at one side thereof is a barrel 58 provided at its upper end, as particularly shown in Figure 3, with a bearing 59. The plate is formed centrally with a bearing 60 projecting into the barrel 53 and extending through said plate is a cap screw 61 threaded into the boss

55, rigidly connecting the plate with the tube 21. Journaled through the bearings 54 and 60 is a shaft 62 upon which is a pinion 63 within the barrel 53 meshing with the rack 32 of the sleeve 26. Freely mounted upon the shaft to lie within the flange 57 of the guard plate is a gear 64 through which is formed an annular series of spaced openings 65, the screw 61 being removable through one of said openings, and overlying the gear is a face plate 66 keyed to the shaft to turn therewith. Fixed upon the shaft to abut the hub of this face plate is a squared head 67 and formed on the outer side of the plate near the periphery thereof is a boss 68. Slidable through this boss is, as particularly shown in Figure 4, a pin 69 in which are formed spaced annular grooves 70 and mounted upon the plate to engage in these grooves selectively is a spring pressed ball or detent 71. The pin is adapted to selectively engage in the openings 65 of the gear 64 so that said pin may be shifted inwardly into any one of said openings for coupling the face plate with the gear and consequently forming a driving connection between the shaft 62 and the gear. On the other hand, by retracting the pin to free the gear, the shaft may be turned independently of said gear, it being understood, of course, that the detent 71 will lock the pin when shifted inwardly or when retracted.

Journaled at one end in the bearing 59 of the barrel 58 and at its opposite end in the bearing 50 of the plate 49 is, as particularly shown in Figure 3, a shaft 72 in the lower end portion of which is formed a longitudinally extending slot 73 and freely mounted on the shaft to rest against the plate 49 is a gear 74 in which is formed a slot 75. Fixed upon the shaft 51 to mesh with this gear is a pinion 76 above which is arranged a second pinion 77 and loosely mounted upon the shaft 72 to rest against the gear 74 is a gear 78 meshing with the latter pinion. The gear 78 is formed in its lower side with an annular recess 79 and entering said recess through the hub of the gear is a slot 80. Fixed to the shaft 72 to coact with the gear 78 is a collar 81 holding the shaft against downward movement while upon the lower end of said shaft is arranged a collar 82 limiting the shaft against upward movement and fitting over the plate 49 to house the pinions 76 and 77 as well as the gears 74 and 78 is a housing cap 83 provided in its top wall with an opening snugly receiving the hub of the gear 78 therethrough. Slidable upon the shaft 72 is a sleeve 84 and connected at one end to said sleeve is a key 85 slidable in the slot 73 of the shaft. At its upper end, this key is provided with a lug 86 extending through the wall of the sleeve while at its lower end the key is provided with a somewhat longer lug 87 adapted to engage in the

slots 75 and 80 of the gears 74 and 78 respectively, but of a size to be freely received within the recess 79 of the latter gear. Formed in the key at its rear edge is a plurality of longitudinally spaced notches 88 and mounted on the shaft 72 to engage in said notches selectively is a spring pressed ball or detent 89. Keyed upon the upper end portion of the shaft 72 within the barrel 58 is a worm 90 meshing with the gear 64 and fitting in the lower end of the barrel is a bearing ring 91 surrounding the shaft and held in position by a binding screw 92 extending through the wall of the barrel.

15 I further provide, as particularly shown in Figure 8, an operating crank 93 for the machine. This crank is formed of mating inner and outer sections, one provided with a longitudinally directed medial channel 94 and the other provided with a longitudinally extending rib 95 slidably engaging in said channel. Formed in the meeting ends of the sections are spaced bolt openings and selectively engageable through said openings is a bolt 96, this construction providing an arrangement whereby the effective length of the crank may be readily adjusted. The inner section of the crank is formed with a head 97 adapted to fit the squared outer end 20 of the shaft 44 as well as the squared head 67 of the shaft 62 while the outer section of said crank is provided with a handle 98.

25 As will now be readily understood in view of the preceding description, when the pin 69 is shifted inwardly to coact with the gear 64, rotation of the shaft 72 will serve to turn the worm 90 and rotate the gear 64 for turning the shaft 62. Rotation of this latter shaft will, of course, cause the pinion 63 to 30 coact with the rack 32 of the sleeve 26 of the boring bar for feeding the bar longitudinally. Furthermore, as will also be understood in view of the preceding description, when the shaft 44 is rotated, the shaft 51 will be coincidentally revolved so that in 35 order to effect feeding of the boring bar coincident with the rotation thereof, it remains to couple the shaft 51 with the shaft 72. In this connection particular attention is directed to Figure 3 of the drawings. In the 40 position of the key 85 illustrated, it will be noted that the lug 87 of said key is disposed within the recess 79 of the gear 78, this being the neutral middle position of the key, so that when said gear is turned by the pinion 77 upon the shaft 51, the gear will merely 45 revolve upon the shaft 72. However, by shifting the slide 84 upwardly, the key may be elevated to ride the lug 87 thereof into the slot 80 of said gear, the detent 89 then engaging in the lowermost of the notches 88 in the key for holding the key elevated. In 50 this position of the key, said key will then form a driving connection between the gear 78 and shaft 72 so that when the crank 93 is 55 applied to the squared end of the shaft 44 and this shaft is turned for revolving the boring bar, the shaft 72 will be driven for feeding the bar. A smooth, steady, continuous feed is thus insured since turning of the 60 boring bar and driving of the feed mechanism are directly correlated. By shifting the sleeve 84 downwardly, the key may be lowered from neutral position to ride the lug 87 thereof into the slot 75 of the gear 74, 65 the detent 89 then engaging in the uppermost of the notches 88 of the key. In this lowered position of the key, the gear 74 will then be coupled with the shaft 72 so that this shaft will be driven from the shaft 51 and 70 attention is now directed to the fact that the gear 74 is somewhat smaller than the gear 78 while the gear 76 is somewhat larger than the gear 77. The relative size of these gears is such that when the key 85 is shifted downwardly to coact with the gear 74, the shaft 72 will be turned at a somewhat greater speed than when the key is shifted upwardly to coact with the gear 78. The rate of feed of the boring bar may thus be varied for a 75 constant rate of rotation of said bar, the elevated position of the key providing a slow feed and the lowered position of the key providing a faster feed.

80 As will thus be seen, when the shaft 44 is rotated, the boring bar will be advanced for advancing the cutter head 36 into the cylinder. However, since it is seldom possible to complete the reborning of a cylinder at one 85 operation without examining the cylinder at various intermediate stages of the work, I have provided means whereby the boring bar with its cutter head may be backed out of the cylinder. To effect this result the pin 69 is retracted to free the gear 64. The 90 crank 93 is then applied to the squared head 67 upon the shaft 62 when the shaft is counter-rotated. Counter-rotation of this shaft will, as will be seen, serve to retract the boring bar and consequently pull the cutter 95 head out of the cylinder, and, in this connection, particular attention is directed to the fact that as the boring bar is withdrawn, said bar will not be revolved so that the cutter head will also not be revolved to cause 100 possible scoring of the cylinder wall. As will be perceived, the cutter head may be withdrawn from the cylinder quickly and easily and after the cutter head has been so withdrawn, the gear case 16 may be detached from the base 10 when the progress 105 of the work may be inspected. Since removal of the gear case from the base will not molest the centering of the base with respect to the cylinder, the gear case may simply be replaced upon the base and the work 110 continued without the necessity for again centering the cutter head.

115 Having thus described the invention, what is claimed as new is:

1. In a cylinder reboring machine, a gear case having a bearing tube upstanding therefrom, a boring bar journaled in said tube extending through the gear case, means housed by the gear case coacting with the bar for rotating said bar, a sleeve upon the bar slidably fitting in said tube and provided with a rack, means upon the tube coacting with said sleeve holding the sleeve against rotation, and feed mechanism driven by said first mentioned means including a pinion coacting with said rack for advancing the bar.

2. In a cylinder reboring machine, a gear case, a rotatable boring bar extending therethrough, means housed by the gear case for rotating said bar, a bearing upstanding from the gear case and provided with an end plate, a shaft journaled in said bearing driven by said means, a second shaft having driving connection with the boring bar for feeding the bar and journaled at one end upon said plate, coacting gears associated with said shafts, and means for coupling and uncoupling certain of said gears for varying the rate of feed of the bar for a constant rate of rotation thereof.

3. In a cylinder reboring machine, a gear case, a rotatable boring bar extending therethrough, means housed by the gear case for rotating said bar, a bearing upstanding from the gear case and provided with an end plate, a shaft journaled in said bearing driven by said means, a second shaft having driving connection with the boring bar for feeding the bar and journaled at one end upon said plate, coacting gear associated with said shafts, means for coupling and uncoupling certain of said gears for varying the rate of feed of the bar for a constant rate of rotation thereof, and a housing mating with said plate enclosing the gears.

4. In a cylinder reboring machine, a gear case, a rotatable boring bar extending therethrough, means including a drive gear housed by the gear case for rotating said bar, the gear case being provided with an upstanding gear housing, a cover plate closing said housing and provided with an upstanding bearing, a shaft journaled through said bearing, a gear on said shaft within the housing meshing with said first mentioned gear, a second shaft having driving connection with the boring bar for feeding the bar, and coacting gears associated with said shafts normally coupling the shafts.

5. In a cylinder reboring machine, a gear case, a rotatable boring bar extending therethrough, means including a drive gear housed by the gear case for rotating said bar, the gear case being provided with an upstanding gear housing, a cover plate closing said housing and providing with an upstanding bearing formed at its upper end

with an end plate, a shaft journaled through said bearing, a gear on said shaft within the housing meshing with said first mentioned gear, a second shaft journaled at one end upon said plate and having driving connection with the boring bar for feeding said bar, and coacting gears associated with said shafts normally coupling the shafts.

6. In a cylinder reboring machine, a gear case, a bearing tube upstanding therefrom, a rotatable boring bar journaled in said tube extending through the gear case, means for rotating said bar housed by the gear case, a bearing mounted near the upper end of said tube and provided with a barrel, a shaft journaled through said bearing and having driving connection with the bar for feeding the bar, a second shaft journaled at one end upon said barrel and having driving connection with said first mentioned means, and a worm upon the latter shaft housed in said barrel and having driving connection with said first mentioned shaft.

7. In a cylinder reboring machine, a gear case having an upstanding bearing tube, a rotatable boring bar extending through the gear case and accommodated in said tube, means for rotating said bar housed by the gear case, a guard plate secured to the tube and provided with a bearing, a shaft journaled through said bearing and having driving connection with said boring bar for feeding the bar, a gear loose on said shaft partially housed by the plate, an element fixed to the shaft and provided with means detachably engageable with said gear coupling the gear and shaft to turn in unison, the plate being provided with a barrel, a second shaft journaled at one end upon the barrel, a worm upon the latter shaft meshing with said gear, and a driving connection between the latter shaft and said first mentioned means.

8. In a cylinder reboring machine, a rotatable boring bar, a rack for reciprocating the bar, a shaft parallel to the bar, a pair of shafts geared respectively to the boring bar, and to the rack both of said shafts being also geared to the first-named shaft and projecting in the same direction from the machine, and a single detachable handle adapted to be placed on either shaft for driving it manually, substantially as set forth.

9. In a cylinder reboring machine, a gear case having a bearing tube upstanding therefrom, a boring bar journaled in said tube extending through the gear case, means housed by the gear case coacting with the bar for rotating said bar, a sleeve upon the bar slidably fitting in said tube, and feed mechanism driven by said rotating means for the boring bar including a shaft extending crosswise of the boring bar, gearing connecting the shaft respectively to said sleeve

and to said rotating means for the boring bar said shaft being formed to receive a handle for independent manual operation, and a clutch on the shaft for disconnecting said shaft from the rotating means for the boring bar, substantially as set forth.

10. In a cylinder reboring machine, a gear case having a bearing tube upstanding therefrom, a boring bar journaled in said tube extending through the gear case, means housed by the gear case coating with the bar for rotating said bar, a sleeve upon the bar slidably fitting in said tube, and feed mechanism driven by said rotating means
15. for the boring bar including a shaft extending crosswise of the boring bar said shaft connected to said sleeve, a worm-gear loose on the shaft, a worm meshing with the worm-gear said worm being driven from the 20 gearing for rotating the boring bar, a face plate fixed to the shaft, and a pin on the face plate adapted to engage in any one of a series of holes in the worm-wheel, substantially as set forth.
25. 11. In a cylinder reboring machine, a boring bar, a gear case including an upright bearing tube for the boring bar, a feed shaft parallel to the boring bar, common means for driving the boring bar and the feed 30 shaft, a worm gear driven by the feed shaft, a horizontal shaft loosely supporting said worm gear, swivelling connections between the horizontal shaft and the boring bar constructed and arranged to raise and lower the 35 boring bar, a face plate fixed to the horizon-

tal shaft, and a clutch element adapted to connect the face plate to the worm gear, substantially as set forth.

12. In a cylinder reboring machine, a vertical boring bar, a gear case having a bearing for said bar, a cap for the open upper end of the gear case, a driving shaft for the bar journaled in said cap, a tube rising from the cap said bar being journaled in the tube, a lateral extension on said case open 40 at the top, a cover plate closing said opening, an end plate above the cover plate and integral therewith, a housing on the end plate, change speed gearing in the housing, a vertical shaft journaled in said plate and 45 extending into said housing for driving said gearing said vertical shaft being geared to said driving shaft, a vertical shaft driven by said change speed gearing said shaft being journaled at its foot in said end plate, and feeding means for the boring bar driven by said last-named shaft, substantially as 50 set forth.

13. In a cylinder reboring machine, a boring bar, a beveled gear encircling the bar and secured thereto, feeding means including a shaft parallel to the boring bar, a beveled gear on the shaft, a driving shaft having its axis in the same plane with those of 60 said bar and said first-named shaft, and a driving pinion having oppositely beveled sets of teeth engaging those of said gear and pinion, substantially as set forth.

In testimony whereof I affix my signature.
FREDERICK T. FLINCHBAUGH. [L.S.]
